UNITED STATES PATENT OFFICE.

GEORGE R. PYPER, OF SALT LAKE CITY, UTAH.

SIGN.

1,382,225.

Specification of Letters Patent. Patented June 21, 1921.

Application filed November 21, 1919. Serial No. 339,670.

To all whom it may concern:

Be it known that I, GEORGE R. PYPER, a citizen of the United States, residing at Salt Lake City, in the county of Salt Lake 5 and State of Utah, have invented new and useful Improvements in Signs, of which the following is a specification.

This invention relates to improvements in illuminated and animated signs and is 10 designed to produce a simple and novel animating member provided with vanes extending therefrom so that it can be readily rotated by a current of air, as from an electric fan.

15 In the drawings: Figure 1 is a front elevation of a sign embodying the present invention, the illuminating devices and parts of the operating mechanism being shown by dotted lines.

20 Fig. 2 is a section on the line 2—2 of Fig. 1, showing the manner of mounting the rotatable member and the circuit breaker operated thereby.

25 Figs. 3 to 8 inclusive illustrate different designs of the front of the rotatable member.

Referring to the drawings in detail, wherein like characters of reference denote corresponding parts, the reference character 30 15 indicates the sign member, which, as shown and described in my Patent No. 1,251,282, dated December 25, 1917, may be constructed of cardboard or other material and provided with openings 16, 35 for the passage of light, the said openings being preferably covered by a strip of translucent material 17. These openings may be arranged after the manner of the patent previously referred to, or they may 40 constitute a border for the sign member, as shown in Figs. 1, 2 and 3.

Located at the rear of the sign member 15, is a casing 18, the said casing having mounted therein a shaft 19, the latter 45 being arranged substantially at right angles with respect to the sign. Mounted for free rotation upon the shaft 19, is a member 20. This member, as shown in Figs. 3 to 8, may be provided with a plurality of spirally or 50 radially arranged openings 21, and upon its rear face with vanes or projections 22. These vanes or projections are so arranged that a current of air directed toward preferably one half of the rear face of the rotatable member 20 will cause the latter to rotate upon the shaft 19, the speed of such

rotation being governed by the strength of the current of air and the arrangement of the vanes or projections 22 and the relative direction of the current of air. The shaft 60 19 has mounted thereon sleeves 23, which serve to prevent longitudinal movement of the member 20 upon the said shaft.

Positioned within the casing 18, behind the rotatable member 20, is a source of light 65 24, herein shown as an electric bulb. Any number of bulbs desired may be arranged to provide the light and they may be of the same colors, or of different colors, as shown in my previous patent.

Also arranged behind the sign member 15, is a casing 25, within which is arranged a source of light in the form of incandescent lamps 26, the said casing being provided with an extension 27, having also arranged 70 therein incandescent lamps 28. The lamps 26 are designed to illuminate advertising, or other matter, formed by perforating the sign member and covering the said perforations with suitable translucent material, or 75 the advertising or other matter may be formed by any other desired means. There is illustrated in the drawings the extension 27, which is provided with an opening 29, which is covered by suitable translucent material, the said opening being arranged to represent a shaft, or bolt of lightning, the effect being increased by illuminating and extinguishing the lamps 28 in a manner to 80 be later described.

85 For the purpose of operating the rotatable member 20, there is provided an electrically operated fan 30, which is arranged within the casing 18 in a manner to direct a current of air upon the said rotatable 90 member, the current for operating this fan being supplied from any suitable source, while not so illustrated in Fig. 2, the fan is 95 preferably placed in the bottom of the casing with its armature shaft at right angles to the axis of the rod 19, so that a strong current of air will strike the vanes 22 on the lower half only of the disk 20.

It is also the purpose of the invention to alternately illuminate and extinguish the 105 lamps 24, 26 and 28, and to accomplish this, there is provided a circuit breaker, which is connected with and operated by the rotatable member 20. This circuit breaker is in the form of a cylinder or wheel 31, which 110 may be formed on or detachably secured to the rotatable member and provided around

its periphery with spaced contact members 32, suitably insulated apart. The extremities of the contact members 32 project outwardly beyond the periphery of the cylinder 5 or wheel 31, and are adapted to contact with a stationary contact member or brush 33. This contact member or brush 33 is mounted upon an arm 34, secured upon the rod 19. The contacts 32 will be placed in branches 10 containing some of the lamps 24, 26 and 28 so that they will be alternately illuminated in a manner well known to those skilled in the art.

In Fig. 5 of the drawings there is illustrated 15 a direct drive for the shaft 19, which carries the rotatable member 20. This consists in securing a pulley 40 to the member 20 and operating the same through the medium of a belt 41, driven by a pulley 42, 20 from a shaft 43, which is in turn operated by an electric fan or motor which operates the rotatable member. The diameters of the pulleys 40 and 42, are such as to cause the shaft 19 to rotate at a greater speed than 25 the shaft 43. In this form of the invention, the circuit breaker, which is indicated at 44, is identical in construction with the one previously described, but instead of being mounted upon the shaft 19 is mounted upon 30 the shaft 43.

Figs. 3 to 8 inclusive illustrate different forms of the rotatable member 20, any one of which may be substituted for the one shown in Figs. 1 and 2, by removing the 35 shaft 19 from its bearings, and replacing it with the desired form of member 20 to meet

the particular requirements of the part to be animated.

The invention is susceptible of various changes in its form, proportions and minor 40 details of construction and the right is herein reserved to make such changes as properly fall within the scope of the appended claims.

Having described the invention, what is 45 claimed is:

1. In an apparatus of the class described, a rotatable animating member having portions thereof removed to permit the intermittent passage of light therethrough as it is rotated and having radially disposed 50 vanes extending laterally from the body thereof to be engaged by a current of air for rotating the same, in combination with a casing having a display surface parallel to the animating member, and a light in the 55 casing back of the animating member, substantially as and for the purpose described.

2. An illuminated sign embodying a member having light transmitting portions, a source of light spaced from said member, a 60 rotatable member interposed between the first mentioned member and the source of light for alternately cutting off and permitting the light's rays to reach the said first mentioned member, laterally extending radially disposed vanes carried by the rotatable member, and means for supplying a current of air to the said rotatable member 65 to operate the same.

In testimony whereof I affix my signature. 70

GEORGE R. PYPER.
